UNITED STATES PATENT OFFICE.

KIRKLEY HYDE, OF LOWELL, MASSACHUSETTS, ASSIGNOR OF THREE-FOURTHS TO JAMES W. BENNETT, ALBERT M. MOORE, AND FREDERICK TAYLOR, ALL OF SAME PLACE.

WOOD-RIM PULLEY.

SPECIFICATION forming part of Letters Patent No. 309,144, dated December 9, 1884.

Application filed May 12, 1884. (No model.)

To all whom it may concern:

Be it known that I, KIRKLEY HYDE, a citizen of the United States, residing at Lowell, in the county of Middlesex and Commonwealth of Massachusetts, have invented certain new and useful Improvements in Wood-Rim Pulleys, of which the following is a specification.

My invention relates to that class of wood-rim pulleys in which the ends of the middle or foundation fellies are notched to receive ledges formed on the outer edges of the spider-arms; and it consists in means whereby the ends of said foundation-fellies may be tightened on said ledges.

In the accompanying drawings, Figure 1 is a side elevation of such a pulley, a part of the outer fellies thereof being broken away to show the ledges at the ends of the arms, and the notches and slot in the ends of the foundation-fellies, and the tightening bolts and nuts; Fig. 2, a central cross-section of the same on line *x x* in Fig. 1.

A is a metallic spider consisting of the hub *a* and the arms *a'*, of any usual construction, except that the outer ends of the arms are each provided on each edge thereof with a wedge-shaped ledge, *a''*. The middle or foundation fellies, *B*, are each provided at each end with a notch, *b*, adapted to receive one of the wedge-shaped ledges *a''*, and are otherwise shaped to reach over the outside of the end of the arm and meet the adjacent foundation-felly at the middle of said arm, as shown in another application filed herewith. One end of each felly is also slotted at *b'* longitudinally back from the deepest part of the notch for a sufficient distance to allow the sides of the slot to be sprung toward each other, and a screw-bolt, *C*, is passed radially through the slotted end of the felly at right angles to the slot, the head of the bolt being let into the

outside of the felly. A nut, *c*, is placed on the inner threaded end of the bolt, by turning which nut the sides of the slot are drawn together, and the sides of the V-shaped notch are pressed down upon the wedge-shaped ledge, crowding the felly endwise back against the next adjacent arm and securing the felly firmly in place. The nut *c* is prevented from loosening by a check-nut, *c'*, which is turned up on the bolt *C* against the nut *c*.

The felly-tightening device above described avoids the necessity of fitting the foundation-fellies so accurately to their places between the arms, and of crowding them to their places by the use of a powerful press. The middle fellies form a foundation, to which the outer fellies are secured by nails and glue in the usual manner, and the rim thus formed is then turned true.

I claim as my invention—

1. The combination of the metallic spider provided with wedge-shaped ledges at the outer ends of its arms, and the foundation-fellies provided with notches and with longitudinal slots leading into said notches, and means, substantially as described, of drawing the sides of said slots toward each other and of closing the sides of said notches upon said ledges, as and for the purpose specified.

2. The combination of the metallic spider provided with wedge-shaped ledges at the outer ends of its arms, and the foundation-fellies provided with notches and with longitudinal slots leading into said notches, and bolts passed through the slotted ends of said fellies at right angles to the slots and the nuts, as and for the purpose specified.

KIRKLEY HYDE.
